UNITED STATES PATENT OFFICE.

WILLIAM K. LIGGETT, OF COLUMBUS, OHIO, ASSIGNOR TO THE JEFFREY MANUFACTURING COMPANY, OF COLUMBUS, OHIO.

SINGLE-ROLL CRUSHER.

1,339,938.

Specification of Letters Patent.

Patented May 11, 1920.

Application filed July 10, 1916. Serial No. 108,486.

To all whom it may concern:

Be it known that I, WILLIAM K. LIGGETT, a citizen of the United States, residing at Columbus, in the county of Franklin and State of Ohio, have invented certain new and useful Improvements in Single - Roll Crushers, of which the following is a specification, reference being had therein to the accompanying drawing.

10 This invention relates to coal crushing apparatus and particularly to machines known as single roll crushers.

The widely extended use of automatic stoking furnaces has created a large demand 15 for coal crushed to a small and uniform size. When the coal crushing machines heretofore manufactured have been adjusted to produce the desired fineness of product, their capacity has usually been reduced beyond 20 the limit of profitable operation and an unduly large portion of the coal has been reduced to dust.

The common expedient by which these difficulties are avoided is the use of two 25 crushing machines, one adapted to crush large lumps to a comparatively small size being placed over a second machine which is adapted to reduce the product of the first machine to the size required. Such a double 30 machine is necessarily expensive and requires a relatively powerful driving mechanism. In the patent to Whiting, No. 1,045,763, is disclosed a machine comprising a roll rotating adjacent a stationary breaker 35 plate wherein the surface of the roll is thickly set with a large number of relatively small crushing teeth and a much smaller number of relatively long hook-shaped teeth, the hook-shaped teeth serving to draw 40 the larger fragments of the coal down into the machine to be crushed, and the small crushing teeth to crush it to the desired size. A smooth breaker plate is normally supported 45 in such manner that there shall be only a running clearance between its lower part and the tops of the crusher teeth. In order that the longer hook-shaped teeth may 50 pass, grooves are provided in the breaker plate, and the proportions of the teeth and 55 grooves are such that there shall be only the necessary running clearance and the grooves shall be no wider than the greatest desired dimension of the fragments of coal in the product. By this arrangement of parts the 55 throat through which the coal passes affords

no opening through which fragments larger than the desired limit may pass. Such machines have proven satisfactory within certain limits of operation, but when it has been desired to reduce the fineness of the 60 product below a certain maximum, three quarters of an inch say, the capacity of the machines has been reduced beyond the limits of profitable operation.

It is the principal object of this invention 65 to provide a machine of relatively large capacity, which shall be adapted to take run of mine coal, including both large and small fragments, and, by a single operation, reduce it uniformly to the small size suitable 70 for modern automatic stoking furnaces.

A further object is to produce a machine 75 of simple design and great strength in which the parts subjected to the greatest wear may be readily and conveniently renewed.

Other objects will appear in the following specification, wherein is set forth the preferred embodiment of my invention, reference being had to the accompanying drawings of which—

80 Figure 1 is a general plan view of a machine embodying my present invention.

Fig. 2 is a side elevation of the machine shown in Fig. 1.

Fig. 3 is a transverse sectional view taken 85 along the line 3—3 of Fig. 1.

Fig. 4 is a perspective view of the feeder roll.

Fig. 5 is a perspective view of the breaker 90 plate.

Referring to the drawings, 1, 1 are the end frames upon which the crushing mechanism is mounted. Journal bearings 2 and 3 are formed in these end frames and in these bearings are mounted the crushing roll shaft 95 4 and the feed roll shaft 5. The bearings are supplied with the customary removable caps in order that the machine may be easily taken apart. Keyed to the shaft 5 is a pulley wheel 6 adapted to be connected by a 100 suitable belt with any convenient source of power by which the machine may be driven. At the end of the shaft 5 opposite to the pulley 6 is mounted a spur pinion 7 which engages with a gear 8 attached to the roll 105 shaft 4 to drive it. Mounted upon the shaft 4, between the bearings 2, is a drum or roll 9 around the periphery of which is arranged segmental plates 10 which are secured in place by the radial bolts 11. Upon the outer 110

surface of the plates 10 are formed elongated sharp-edged ribs 12 extending parallel to the axis of the roll and, preferably, from end to end thereof. Preferably the front sides of 5 the ribs are approximately radial to the axis of the roll. As will later appear, the ribs coöperate with other parts in the crushing of the coal and the radial and circumferential dimensions of the ribs bear a definite 10 relation to the desired size of the product.

Attached to the frame members 1 are removable end plates 13 and a rear cover plate 14 which serve to inclose the upper portion of the roll. This construction provides 15 removable plates which, when in place, seal the chamber within which the roll operates, thereby preventing the escape of dust, and, when removed, allow access to the bolts 11 so that the segmental sections 10 may be removed 20 or replaced without the entire dismantling of the machine. A hopper 15 is attached to the upper edge of these plates and through this hopper is introduced the coal to be crushed.

25 A breaker plate 16 is pivotally supported on a transverse shaft 17 at the upper front side of the machine, being disposed so that it and the roll form opposite, downward converging walls of a passage through which 30 the coal moves to the final crushing points at the lower side of the plate. Said plate is provided at its lower side with a renewable shoe 18 the entire operative surface of which is formed with elongated sharp-edged ribs 35 19. These ribs are disposed in planes at right angles to the ribs 12 on the roll and extend closely adjacent to the last named ribs, the two sets of ribs coöperating in a peculiar manner, as the roll turns, to crush 40 the coal to a uniform size. As in the case of the ribs of the roll, the dimensions of the ribs 19 bear a definite relation to the size of the product. The shoe 18 is beveled along its top and bottom edges to engage the 45 clamping surfaces 20 and 21 formed on the breaker plate 16 and the clamping plate 22 respectively. The clamping plate 22 is secured to the lower edge of the breaker plate 16 by a plurality of clamping bolts 23 by 50 which it may be drawn against the renewable shoe 18 to lock it securely in place.

A shaft 24 extends through the breaker plate 16 near its lower end, and upon the projecting ends of this shaft are mounted 55 the eye bolts 25 which extend rearwardly through the lugs 26 of the frame members 1. Springs 27 are placed upon the extremities of these eye bolts outside the lugs 26 and are retained in place by nuts 28 by the adjustment of which the tension of the spring 60 27 may be varied. This provides a cushioning of the breaker plate so that when an unusually hard piece of material is passed between the roll and the breaker plate, the 65 breaker plate may yield to relieve the strain

without damage to the machine, after which the springs will immediately return the breaker plate to its operative position.

It has been found that when a crushing roll such as described is provided with ribs 70 of a size appropriate to the production of finely crushed coal, the larger lumps will roll upon the top of the crushing roll and not be drawn down into the machine to be crushed. To overcome this difficulty I have 75 provided a feeder roll 29 mounted upon the shaft 5 intermediate the journal bearings 3. In order that the roll 29 may be securely held against rotation relative to the shaft 5 that portion of the shaft which is intermediate the bearings 3 is formed square, and the roll is built up of sections 30 each of which is provided with a square aperture 31, through which the shaft 5 extends. Upon 80 each of these sections 30 is formed a narrow, radially elongated hook-shaped tooth 32 adapted to engage the larger pieces of coal and force them downward between the roll and breaker plate. These sections are so placed on the shaft 5 that each tooth 32 85 is angularly displaced 90° from the next adjacent tooth, thus forming a spiral line of teeth around the roll. Formed on the face of the breaker plate 16 is a transverse ridge 33 the upper face of which conforms closely 90 to the curvature of the roll 29 to prevent the passage of coal between the roll 29 and the breaker plate 16. The ridge 33 extends well under the feeder roll 29 and the lower face of the ridge forms an upright abutment wall 100 for the coal at points between the crusher roll and a vertical plane through the axis of the feeder roll. To permit rotation of the roll 29 slots 34 are formed in the ridge 33, and preferably in the adjacent parts of the 105 body of the breaker plate 16, these slots permitting the passage of the elongated feeder teeth 32. As these teeth move downward and pass into the slots, it will be seen that they coöperate with the aforesaid abutment 110 wall on the breaker plate to effectively crowd the coal downward in the tapering passageway toward the final crushing points. In this positive feeding action of the teeth 32 in coöperation with the breaker 115 plate, many of the larger pieces of coal are partially crushed and the downward movement of the mass accordingly facilitated. Of course, in this downward feeding of the coal mass there is effective coöperation between the feeder roll 29 and the crushing roll 9; for, while the relatively low ribs of the crusher roll are not capable alone of feeding the larger masses of coal downward, they aid materially in the feeding action of 120 the coal 29 as will readily be understood from an inspection of Fig. 3. The upward movement of the teeth 32 of the feeder roll has no effect, of course, upon the coal because the teeth are incased during such 125 130

movement within the slots of the breaker plate.

In practical operation machines of this character are commonly arranged to receive the coal which is to be crushed in relatively large masses. The hopper 15 is often so located as to receive the coal from drop bottom cars or from large grab buckets or by other rapid methods of handling. In such cases there will often be a load of several tons of coal directly upon the crushing and feeding rolls. As the two rolls revolve toward each other and downward, the lower parts of the superimposed coal mass are engaged and drawn down into the tapering passageway between the crusher roll and the breaker plate, the larger pieces of coal being effectively forced downward and partially crushed, as above described, by the elongated teeth of the feeder roll, while the forwardly inclined ribs on the crusher roll exert a downward feeding action on the smaller particles of the coal.

In the downward movement of the coal through the machine, it comes to the final crushing points between the ribs of the roll and the ribs on the shoe 18 of the breaker plate. The action of the two sets of ribs on the coal is peculiar; the ribs, disposed as they are at right angles to each other, tend to divide the stream of coal along lines at right angles to each other, cutting the coal into fragments of a general cubical form rather than indiscriminately mashing it. Hence, while the crushing action of the ribs is highly effective, there is much less tendency to reduce much of the coal to dust than there is in the case of prior machines in which the roll is formed with isolated teeth working on a relatively plain or smooth faced breaker plate. It will be understood that the ribs both on the roll and on the breaker plate are spaced apart a distance approximately equal to the maximum permissible dimensions of the fragments of the product, and since, when the machine is adjusted for fine crushing, there is no space for larger fragments to pass through, the fineness of the product is assured. Furthermore, the coöperative action of the two sets of ribs is such that while there is a relatively slight tendency to reduce the coal to dust, and while the action is remarkably uniform, the capacity is not unduly reduced by the close setting of the plate and roll as in prior machines.

In the preferred form of construction illustrated in the drawings the crushing ribs on the roll are shown as extending continuously the full length of the roll, but in referring to the ribs both of the roll and of the breaker plate as "elongated," I intend simply to distinguish them from isolated teeth such as have been used on the crushing rolls of prior machines and by the term

"elongated" mean to indicate that the working edges of the ribs are elongated to a length greater than the distance between the ribs on the opposing element of the crusher.

It is to be understood that coöperating sets of crusher ribs, such as are herein set forth, may be utilized in forms of construction differing more or less radically in some respects from the structure herein disclosed, and in my two co-pending applications of even date herewith and bearing the Serial Nos. 108,485 and 108,487, I have shown two other forms of construction in which such ribs are embodied.

What I claim is:—

1. In apparatus for crushing coal, the combination of a frame, two companion crushing elements oppositely mounted in the frame to form a downwardly tapering passage through which the coal passes to the final crushing points, a feeding device supplemental to the roll comprising a series of elongated teeth mounted at the upper end of said passage to rotate around a transversely extending axis to engage the coal and force it downward between the crushing elements, and means to prevent the engagement with the coal of said elongated teeth during the outward and upward parts of the movement of rotation.

2. In an apparatus for crushing coal, the combination of a frame, two companion crushing elements oppositely mounted in the frame to form a downwardly tapering passage through which the coal passes to the final crushing points, and a positively acting feeding mechanism supplemental to the crushing element arranged to operate in the tapering passage way to engage the larger fragments of coal and force them downwardly through the tapering passage.

3. In apparatus for crushing coal, the combination of a frame, a crushing roll rotatably mounted in the frame, a breaker plate mounted in the frame at one side of the roll to coöperate therewith, the said plate and roll forming opposite downwardly converging walls between which the coal passes downwardly to the final crushing points, means for feeding the coal downwardly between said converging walls comprising a transversely extending cylinder rotatably mounted between the crusher roll and the breaker plate and having radially elongated teeth, and stationary means arranged to surround the teeth during their upward movement.

4. In apparatus for crushing coal, the combination of a frame, a crushing roll rotatably mounted in the frame, a breaker plate mounted in the frame at one side of the roll to coöperate therewith, the said roll and plate forming opposite downwardly converging walls between which the coal

passes downwardly to the final crushing points, and means for feeding the coal downwardly between the converging walls comprising a transversely extending cylinder 5 rotatably mounted between the crushing roll and the breaker plate and having radially elongated teeth, the breaker plate being formed adjacent the feeding cylinder with slots into which the said elongated teeth 10 pass during their upward movement.

5. In apparatus for crushing coal, the combination of a frame, a crushing roll rotatably mounted in the frame, a breaker plate mounted in the frame at one side of 15 the roll to coöperate therewith, the said roll and plate forming opposite walls of a downwardly tapering passage through which the coal passes downwardly to the final crushing points, and means for feed- 20 ing the coal downwardly between the con-

verging walls comprising a transversely extending cylinder rotatably mounted between the crushing roll and the breaker plate and having radially elongated teeth, the breaker plate being shaped to form an upright abutment wall disposed beneath the feeding cylinder at points in vertical planes between the crusher roll and the axis of the feeder cylinder and the said abutment wall and adjacent parts of the breaker plate being 25 formed with slots into which the feeder teeth intermittently pass in their rotational movement.

In testimony whereof I affix my signature in presence of two witnesses.
